I. N. W. PORTER,
PAPER CUTTER,
APPLICATION FILED JULY 13, 1915.

1,208,829.

Patented Dec. 19, 1916.

UNITED STATES PATENT OFFICE.

JAMES N. W. PORTER, OF NORFOLK, VIRGINIA.

PAPER-CUTTER.

1,208,829.

Specification of Letters Patent. Patented Dec. 19, 1916.

Application filed July 13, 1915. Serial No. 39,543.

To all whom it may concern:

Be it known that I, JAMES N. W. PORTER, a citizen of the United States, residing at Norfolk, in the county of Norfolk and State 5 of Virginia, have invented new and useful Improvements in Paper-Cutters, of which the following is a specification.

This invention relates to a paper-cutting machine, and is particularly adapted for use 10 to clip the ends of envelopes, or the like, although it may be used for cutting cards, or other stationery.

It is an object of the invention to provide a device whereby envelopes, cards, and the 15 like, may be expeditiously cut in a straight, clear and well-defined line, so that ragged edges and the like are prevented.

It is a further object of the invention to provide a device with a receptacle which 20 receives the cut clippings, and from which the accumulated clippings may be easily extracted or emptied.

Another object of the invention is to provide the device with a base or bed upon 25 which envelopes or cards to be cut are positioned, and which is to receive a suitable advertisement, so that the user of my device has his attention called to the advertisement, photograph, or the like, displayed 30 upon the bed or base.

Other objects of my invention are to provide a device which is simple in construction and arrangement, strong and durable, and which, as the same consists of comparatively few parts, may be manufactured at a 35 minimum cost.

With the above and other objects in view, the invention consists in certain combinations and arrangements of parts which are 40 disclosed in the accompanying drawings, and in which,—

Figure 1 is a perspective view of my improved paper cutter. Fig. 2 is a longitudinal section view through the same. Fig. 3 45 is a side elevation looking at that side of my device on which the knife and clipping receptacle are positioned. Fig. 4 is a transverse section through my device.

Referring more particularly to the drawing, 10 is a base or block upon which the envelopes, cards, or the like, to be cut are positioned preparatory to the cutting operation; 11 is a swinging knife, and 12 the receptacle which catches or receives the clip- 55 pings or cut strips of paper.

The base 10 comprises a block which is

substantially rectangular in cross-section, but which is higher at the rear edge than the forward edge as is shown in the figures, the top face or surface being inclined downwardly toward the front of the device. The inclined top face, intermediate the ends, is recessed, so as to provide a bed 13, and the rib members or ledges 14 and 15 adjacent the upper and lower edges respectively of the top face are undercut or recessed to form 60 grooves, as designated by the numeral 16.

Upon the bed 13 is secured, in any suitable manner, a covering 17, which may be of felt, or other similar material, and this 65 covering extends into the grooves 16 so that its rough edges are hidden from view.

Upon the bed 13, over the felt covering 17 and engaging in the grooves 16 is a transparent plate 18, preferably of glass. An 70 advertisement, photograph, or the like, is placed upon the bed 13 under the transparent plate 18, and this advertisement, etc., is open to the view of the user of my device.

In the present drawings, a card advertisement A is shown positioned under the plate 18, but it is, of course, evident that the felt covering may be dispensed with, and that the base may be constructed to receive any 75 suitable ornament, time-piece, or other article of display. The glass plate 18 presents 80 a neat and smooth surface, which may be readily cleaned, and on which the article to be cut is positioned and at the same time the plate protects the article to be displayed 85 from dust and dirt and the article displayed 90 is in such position that the user of my device will have his attention called to it. The transparent plate 18 is retained against 95 lateral displacement by means of a corner or angle-piece 19 secured in place by screws 20.

When it is desired to renew or change the 100 article displayed, it is merely necessary to remove the screws 20 and angle-piece 19, withdraw the plate 18 from the grooves 16 and replace the displayed article with a second one.

Upon the side of the base 10 opposite that 105 of the angle piece 19 is a stationary blade member 21 which extends slightly above the level of the bed 13, so that the transparent plate 18 cannot be displaced from engagement with the angle piece 19. The upper edge of the stationary blade member 21 is inclined upwardly and outwardly from the 110 base as designated by the numeral 22, so that an outer knife edge is provided. Pivoted

to the upper end of the blade member 21, by means of a screw, is a swinging knife 11, which works in conjunction with the cutting edge of the blade member 21, so as to cut paper placed therebetween. The swinging knife 11 may be of any suitable configuration or form, but it is preferably of substantial thickness at the upper portion and is beveled downwardly, so as to form a sharp cutting edge. Adjacent its free end, the swinging knife is provided with a handle 23 for manipulating the knife, and preferably this handle is attached to the side of the knife slightly above the longitudinal center line of the same, and the handle 23 is preferably in the form of a knob, so that it extends slightly beyond the plane in which the knife 11 swings, whereby when the knife is depressed the downward pressure thereon tends to deflect the blade inwardly and press the cutting edge of the same against the co-operating stationary blade member 21.

On the side of the base 10, beneath the knife 11 is provided the receptacle 12, for catching or receiving the clippings as they fall after the cutting operation. This receptacle 12 is very simple in construction and is preferably formed of a single sheet of sheet metal, the sheet being bent at right angles along the longitudinal line and having one leg 24 secured to the bottom of the base 10 at the recessed portion 25. Upon the bottom of the base 10 is a covering or pad 26 of soft material to prevent abrasion or scratching of the surface upon which my device is placed. The upper rear corner 27 of the vertical wall of my receptacle 12 is bent inwardly toward the base 10 and is secured thereto by any suitable means, and the forward end of the receptacle is secured to the base by means of a rivet 28. The rear of the receptacle 12 is open so that by merely raising the forward end of my device, and thus tilting the same backwardly, the clippings by gravity fall from the receptacle, and to prevent clogging of the clippings within the receptacle, the base is cut away as at 29.

It will be noted that my base is so constructed as to permit envelops or the like to be positioned thereon in a ready manner, and at the same time, an advertisement or other article of display may be placed beneath the glass and such article of display is brought to the attention of the user. The ledges or rib members 14 and 15, serve to hold the plate of glass on the bed over the article of display, and at the same time serve as guides or flanges for the edges of the envelop or paper to be cut, so as to maintain the paper

in proper position during the cutting operation. The top face of the base is inclined, so that the user of the device, when in sitting position, may look squarely down upon the article displayed, and may readily see that the article being cut is in proper position upon the bed. Cards, envelops, and other kinds of stationery may be cut by my device, and such cards may be cut at any place and at any angle.

The base 10 may be provided with any suitable attachment, and for convenience the upper end of the base is provided with a pin-cushion 30, and also with a rule or line of graduations 31, at the top of the transparent cover or plate 18, whereby the paper cut may be measured to conform to any desired size within the limits of the device.

It is, of course, obvious that my device is susceptible to various modifications and mechanical changes which would be within the spirit of the invention without departing from the scope of the following claims.

What I claim as new is,

1. In a device as specified, a relatively high base having a face adapted to support the paper to be cut, a knife along one edge of the base for cutting the paper, and a relatively narrow receptacle on the side of said base beneath said knife for receiving the cut clippings, said receptacle being open at its rear whereby the same may be readily emptied and said base being cut away adjacent the open end of said receptacle to facilitate emptying of the receptacle.

2. In a device as specified, a base to support papers to be cut, a knife along one edge of the base for clipping said papers, and a relatively narrow receptacle beneath said knife for receiving the clippings, said receptacle being formed from a sheet of sheet metal bent at right angles along a longitudinal line and having one leg attached to the bottom of said base and having its upper rear corner bent inwardly and secured to the upper rear edge of said base whereby said receptacle is open at its top to receive said clippings and the receptacle is open at its rear so that the clippings may be expelled therefrom said base being cut away adjacent the open end of said receptacle to enlarge the opening and facilitate the emptying of said receptacle.

In testimony whereof I have hereunto set my hand in presence of two subscribing witnesses.

JAMES N. W. PORTER.
